UNITED STATES PATENT OFFICE.

OTTO T. LADEMAN, OF MILWAUKEE, WISCONSIN, ASSIGNEE TO MOSEÉ CODE SIGNAL COMPANY, OF MILWAUKEE, WISCONSIN.

SIGNALING SYSTEM.

1,129,805.

Specification of Letters Patent. Patented Feb. 23, 1915.

Application filed April 30, 1912. Serial No. 694,213.

To all whom it may concern:

Be it known that I, OTTO T. LADEMAN, a citizen of the United States, residing at Milwaukee, in the county of Milwaukee and State of Wisconsin, have invented a certain new and useful Improvement in Signaling Systems, of which the following is a full, clear, concise, and exact description, reference being had to the accompanying drawings, forming a part of this specification.

My invention relates to signaling systems and has for its object the provision of an improved system of the step-by-step variety.

My invention has various applications, but to set forth its general features I will describe my invention herein as applied particularly to a system of police call. While describing my invention as used in this particular manner, I do not thereby intend to limit my invention to such use as before stated, but merely describe this particular manner of employing my invention as illustrative.

When my invention is applied to police call systems it is designed to operate signals suitably located about a city in such a manner as to indicate to the police officer on duty within the particular district that he is wanted. These signals are preferably provided at patrol boxes to which the called officer repairs to communicate, preferably by telephone, to headquarters. The signals may be in the form of visual or audible signals as the case may require. In fact, both signals may be used in connection with the same calling device. The visual signal is preferably of the lamp type and in the daytime may be continually illuminated, if desired, or may be flashed intermittently so as

40 to call the attention of the police officer.

At night, I find it of advantage to have the visual signal lamp burn continuously and then whenever the particular officer is desired, to intermittently extinguish and illuminate the particular lamp or lamps to which he may respond. All of the functions aforesaid may be carried on over a single circuit and in addition, this circuit may be used for telephonic purposes if so desired.

I will describe one embodiment of my invention as applied particularly to the flash and alarm system above outlined, in connection with the accompanying drawing illustrating the same diagrammatically.

In the drawing I show a central station A and substations B and C. At each substation I employ a selector herein illustrated diagrammatically of the general type illustrated in Patent No. 970,180, issued Sept. 13, 1910, to W. S. Burnett. This selector has two armatures 1 and 2, which armature 2 is shown twice at each substation in order to more clearly bring out the circuit connections, the illustration being diagrammatic. The selector has two separate magnetic circuits, one comprising the arms 3, 3 in connection with the heel piece 4 and the armature 1. The other magnetic circuit comprises the C shaped core between which the armature 2 is mounted and in response to which this armature 2 moves. A pair of coils 6, 6 constitute the single winding for energizing both of these magnetic circuits. Thus when a current is impressed on the windings 6, if it be of an alternating or similar variety, the armature 1 oscillates back and forth upon its pivot 7. A direct current in the coils 6 holds the armature 1 either in the position shown in the illustration or in its alternative position against the opposite core, depending upon the direction of the current in these coils. A permanent magnet 8 furnishes the polarizing agency as required. The armature 2 is not polarized and moves about its pivot 9 by having its right hand extremity elevated whenever there is any magnetization of the core 5. The armature 2 thus responds and remains in its attracted position even though alternating currents traverse the coils 6. A step-by-step element 10 having a notch 11 is pivoted upon a shaft 12 and is rotated by means of suitable step-by-step mechanism under the control of the armature 1, which step-by-step mechanism is not shown herein but is set forth in the patent to Burnett before mentioned. The right hand extremity of the armature 2 is heavier than the left so that this armature tends to press a projection 13 against the element 10, and if this element 10 is in its proper position, the projection 13 may enter the notch 11 and thus permit the armature 2 to effect certain circuit changes by controlling the springs 14, 15 and 16. An insulating lug 17 is interposed between the spring 14 and the armature 2. Assume then that alternating current impulses are impressed on the line circuit 18 and 19 which unites all of the sta-

80

85

90

95

100

105

110

tions, then the armature 1 will oscillate back and forth in answer to these impulses, the armature 2 in the meantime being attracted and remaining attracted so that the 5 projection 13 may not enter any passing notch 11. Immediately the impulses cease, however, the notch 11 of the particular station desired is directly over the projection 13 and the cessation of impulses permits the 10 armature 2 to move in a clockwise direction, thereby breaking the circuit between the springs 14 and 16 and closing the circuit between the springs 14 and 15. The coils 6 are connected across the line conductors 18 and 15. 19 by means of the conductors 20 and 21.

The armature 2 is shown twice in each 20 substation illustration in order to illustrate the circuit control of this armature, and also to illustrate its exact position in the magnetic circuit. Two contacts 22 and 23 are under the control of a circuit changing arm 24 mounted upon the armature 1. The contact 23 by means of the conductor 25 is connected to one terminal of an alarm signal 26, 25 a further conductor 27 uniting the remaining terminal of said alarm signal with a conductor 28 which together with a companion conductor 29 leads to some suitable source of current supply here shown as a 30 generator 30. A conductor 31 unites the line wire 19 with a relay 32, the other terminal of this relay being connected to ground at 33. The armature 34 of this relay is connected with the conductor 29 and the 35 front contact 35 of this relay is connected by means of the conductor 36 with the spring 14. The spring 15 is connected by means of the conductor 37 with a contact 22. The spring 16 is connected by means of the conductor 38 with a visual signal or lamp 39, the remaining terminal of said lamp being connected by means of the conductor 40 to the conductor 28 leading to the source of current supply.

45 It is now to be assumed, in the preferred layout of a system of this character, that, say thirty-six selectors are connected to the same circuit and that six signals each respond to the same number. The notches 11 50 in the various signal receiving devices responding to different numbers are angularly displaced about the periphery of the elements 10 so that it requires a different number of cycles, that is, positive and negative 55 impulses to call the different signal receiving devices responsive to different numbers. It is thus assumed that, say six devices would have the notch 11 similar to the position it occupies as shown in substation B and 60 the same is true for substation C. The illustration of one selector apparatus, however, is thought sufficient to illustrate the principles involved. We have assumed that the signal receiving device at substation B is 65 No. 2 and the signal receiving device at sub-

station C is No. 6. By this it is meant that it takes two complete cycles, that is, two positive impulses and two negative impulses to align the slot 11 of substation B with the projection 13 and that it takes six cycles to 70 align the slot 11 of substation C with its corresponding projection 13. In the operation of the system it is then desired to signal, let us say, substation B, and all similar substations which require two cycles. After these 75 substations have been properly selected, the signals 39 may be intermittently lighted and extinguished by means of central station apparatus which will be presently explained, or a continuous signal may be given, or an 80 alarm may be sounded. I contemplate a further selection of substations in a novel manner. As before stated, assume that there are thirty-six stations to be accommodated, and six of these to be responsive to a 85 given number of cycles. Assume then that the first one would be No. 2 requiring two cycles and the last one would be No. 7 requiring seven cycles. Each call for No. 2 would actuate six signal receiving devices 90 and the same would be true for stations having the succeeding numbers. There are thus six companion stations for each cycle. Assume now, that a number of stations are to be selected at random simultaneously which 95 are not companion substations in the sense as above stated. To do this I provide additional notches 11 as many as may be required which are provided in the element 10 and which are so placed that they require a number of cycles beyond 7, 7 cycles being assumed for that particular set of companion stations requiring the greatest number of cycles for their normal call. These stations would probably be called according to some 100 predetermined selection agreed upon. For this reason some of the thirty-six selectors referred to would be provided with notches which would respond to eight cycles, some 105 of them would be provided with notches to correspond with nine cycles, and some of the stations might be provided with notches to respond not only to eight, but also to eight and ten, or any definite plurality of cycle numbers selected. Thus, if eight cycles were 110 sent out, a different set of substations would be called, and this number might, if desirable, include all of the substations. From this it will be seen that not only might a certain set of companion stations be selected, 115 but an entirely different selection of a plurality of predetermined stations may be chosen and the corresponding signals operated. The substations B and C are each shown as being provided with additional 120 notches 41 which in this case would respond to ten cycles so that with two cycles, substation B and its companion stations would respond and for six cycles substation C and its companion substations would respond, 125 130

whereas with ten cycles both classes of substations would respond.

In order to send the alternating impulses and also the other signaling currents required, I provide apparatus at the central station whose general characteristics I will now set forth. I provide a circuit controlling switch 42 at the central station which is adapted when closed to connect a battery 43 between the line wire 19 and the ground thereby to control the relay 32 as will presently appear. I also provide at the central station a make and break device consisting of the commutator 44 which through the agency of the battery 45 is adapted to transmit periodic impulses over the line wires 18 and 19 when this commutator is actuated. I provide further at the central station a pole changing device 46 having the collector rings 47, 48 and having a two segment commutator 49, 50, all rotatable with a shaft 51. The semi-circular segment 49 is electrically connected with ring 48 and the semi-circular segment 50 is electrically connected with the ring 47. A sheet of insulation 52 is interposed between the two semi-circular segments 49 and 50. Brushes 53 and 54 are normally, when the device is not in operation, held against the insulation section 52, but when it is in rotation bear alternatively against the segments 49 and 50. Brushes 55 and 56 are associated with the rings 47 and 48 respectively, brush 55 being connected with one terminal of the battery 57 and brush 56 being connected with a spring 58 in co-operative relation with a spring 59 which is electrically associated with the other terminal of battery 57. The spring 58 is joined by means of a strip of insulation 60 with another spring 61, which spring is in co-operative relation with another spring 62. The spring 61 is directly connected to the line wire 19 and the spring 62 is directly connected with the brush 54 and also with one terminal of a condenser 63 and one terminal of an inductive resistance 64. The remaining terminals of the condenser and inductive resistance respectively, are connected to the line wire 18. A suitable counting device set forth in my co-pending application Serial No. 690,727, filed April 15, 1912, is operated to control the number of revolutions of the shaft 51 to thereby determine the number of positive and negative impulses transmitted by means of the sending device operating with this shaft, thereby to control the number of cycles. This particular counting device forms no part of my present invention, and of course, any suitable counting device would answer.

The inductive resistance 64 and condenser 63 are bridged directly across the line wires by the springs 61 and 62 whenever impulses are being transmitted, the condenser serving to obviate the injurious effect of the

spark and the resistance serving to take the discharge of this condenser so that this discharge may not cause what might be an impulse of a half cycle which would erroneously operate the armature 1 to effect circuit closure between contacts 22 and 23. Assume now that it is desired to send two cycles to call substation B, then the lever 65 is operated to close circuit between springs 61 and 62 and springs 58 and 59, and the counting mechanism is operated so that the shaft 51 receives two complete revolutions, thereby sending two positive and two negative impulses over the line wires 18 and 19 through the agency of this pole changing sending device. After the impulses have been stopped, the armature 2 is released by gravity and its projection 13 at station B enters the notch 11 thereby closing circuit between springs 14 and 15. The make and break device 44 is then operated alternately to light and extinguish the lamp 39 as will be presently explained. A second key 66 is provided which controls two springs 67 and 68 joined together by a strip of insulation 69, which springs are in association with additional springs 70 and 71 respectively. This key 66 when operated, connects the make and break device 44 and the battery 45 in circuit with the line wires 18 and 19.

A push button 72 is provided for purposes of changing the polarity supplied by the battery 45 to the line wires 18 and 19 and to this end the push button 72 controls the circuit changing springs 73 and 74 to reverse the connection of this battery to the said line wires. The conductors 75 and 76 connect respectively the free terminal of the battery 45 and the free terminal of the make and break device 44 with the springs 73 and 74. Normally the springs 73 and 74 are in engagement with springs 77 and 78 respectively so that a certain polarity of said battery is impressed by means of the conductors 79 and 80 upon the springs 70 and 71 respectively. When the push button 72 is operated so that springs 73 and 74 engage springs 81 and 82 respectively, then the battery polarity as furnished to the line conductors 18 and 19 is reversed as will be apparent, independently of the key 66.

In the general operation of the system, assume now that the impulse sending device mounted on the shaft 51 is operated to send two cycles, that is, two positive and two negative impulses in alternating order. Then the first impulse serves to attract the armature 2 and this armature is attracted and remains attracted during the time occupied by the sending of these impulses. At the same time the armature 1 oscillates in response to these negative and positive impulses, thereby rotating the element 10 to a position in which its notch 11 is over the projection 13. The impulses having ceased,

armature 2 is withdrawn by force of gravity and the projection 13 enters the notch 11 to thereby open circuit between springs 14 and 16 and to close circuit between springs 14 and 15. The lamp 39 thereby has its circuit opened. It must now be pointed out that the polarity of the current furnished by the battery 45 when sent over the line wire without the operation of the key 72 is of such a character that it will tend to attract the armature 1, or rather maintain the armature 1 in the position it occupies in the drawing which is the position in which that armature is left after the completion of each cycle. Consequently impulses transmitted by the make and break device 44 will not affect the armature 1, but will, in accordance with these impulses, cause the attraction of the armature 2 which thereby periodically closes the circuit through the lamp 39. Thereby this lamp is continually flashed until the patrolman desired responds. It must be pointed out, of course, that before the operation stated can take place, the switch 42 must be in its closed position so that the relay 32 remains attracted. This switch 42 should therefore be closed before the signal sending operation begins, or as before stated, during the night this switch 42 may remain in its closed position so that the lamps 49 burn continually until their particular controlling apparatus is selected to flash this lamp. Now should it be desired to sound the alarm 26, after having selected any given station, it will be apparent that this can be done by reversing the position of the armature 1 or rather, by causing it to occupy its alternative position so that its switch element 24 engages contacts 22 and 23 to close circuit there through, and this movement of the armature 1 is the result of sending a one-half cycle of that polarity which would move this armature into its alternative position. This is accomplished by pressing the push button 72 to thereby reverse the polarity of the current furnished by the battery 45 so that the armature 1 is thereby reversed into its circuit closing position, whereupon the alarm 26 is operated. Lever 65 in this case is left in same position, as when operating pole changer. After any station has been called, I operate the shaft 51 to give it a sufficient number of rotations so as to send a sufficient number of cycles over the line wires to bring all of the elements 10 back to their starting position where they are held, even though the number of cycles sent is in excess of that required to make a complete revolution of this element as clearly explained in the patent to Bennett above cited.

From what has been described, the essence of my invention will be apparent. Likewise its application to a multiplicity of different uses, likewise its modification within the scope of the invention, and

What I therefore claim as new and desire to secure by Letters Patent is:

1. A signaling system having a central station and substations united by a line circuit, a step-by-step device at each substation, said substations being arranged in groups and the step-by-step devices of each group having means whereby the substations of each group are simultaneously responsive to a given selective incoming signal, and means associated with a plurality of step-by-step devices of substations in different groups whereby said last aforesaid plurality of substations respond simultaneously to a different incoming signal. 80

2. A signaling system having a central station and substations united by a line circuit, a step-by-step element at each substation, a circuit changing element under the control thereof, and means controlled at the central station operable over said circuit to set said step-by-step element and to independently control the circuit through said circuit changing element at will without moving said step-by-step element. 90

3. A signaling system having a central station and substations united by a line circuit, a step-by-step element at each substation, electromagnetic means operable with alternating current to set said step-by-step element, a circuit changing element under the control of said element, means at the central station to transmit alternating current over said circuit to set said step-by-step element, and means controlled at the central station and operable over said circuit to independently intermittently operate said circuit changing element. 95

4. A signaling system having a central station and substations united by a line circuit, a step-by-step element at each substation, electromagnetic means operable with alternating current to set said step-by-step element, a circuit changing element under the control of said element, means at the central station to transmit alternating current over said circuit to set said step-by-step element, means controlled at the central station and operable over said circuit to independently intermittently operate said circuit changing element. 100

5. A signaling system having a central station and substations united by a line circuit, a step-by-step element at each substation, a circuit changing element under the control thereof, means controlled at the central station to set said step-by-step element and to independently intermittently operate said circuit changing element, a signal adapted to be intermittently operated under the control of said circuit changing element, 110

120

125

130

to the intermittent control of said circuit changing element.

6. A signaling system having a central station and substations united by a line circuit, a step-by-step element at each substation, means operatively responsive only to alternating current for setting said step-by-step element, said means normally occupying when at rest one of its two alternative positions, a signal under the control of said means, and devices at the central station for impressing current on said circuit to reverse the position of said means to thereby operate said signal.
- 10 7. A signaling system having a central station and substations united by a line circuit, a step-by-step element at each substation, a circuit changing element under the control thereof, and means including a single winding and a plurality of independent magnetic circuits therefor controlled at the central station to set said step-by-step element and to independently intermittently operate said circuit changing element.
- 15 8. A signaling system having a central station and substations united by a line circuit, a step-by-step element at each substation, a circuit changing element under the control thereof, means including a single winding and a plurality of independent magnetic circuits therefor controlled at the central station to set said step-by-step element and to independently intermittently operate said circuit changing element, and a signal adapted to be intermittently operated under the control of said circuit changing element.

9. A signaling system having a central station and substations united by a line circuit, a step-by-step element at each substation, a circuit changing element under the control thereof, means including a single winding and a plurality of independent magnetic circuits therefor controlled at the central station to set said step-by-step element and to independently intermittently operate said circuit changing element, a signal adapted to be intermittently operated under the control of said circuit changing element, and means controlled at the central

station whereby said signal may be continuously operated subject to the intermittent control of said circuit changing element.

10. A signaling system having a central station and substations united by a line circuit, a signal receiving device at each substation having a signal under its control, means to set said signal receiving device and to control the operation of said signal, 55 an interrupter at the central station for impressing impulses to intermittently operate said signal controlling means after setting the corresponding signal receiving device, the setting of the receiving device being also 60 controlled at the central station, and means controlled at the sending station to control said signal independently of the setting of said signal receiving device.

11. A signaling system having a central station and substations united by a line circuit, a signal at each substation, means controlled at the central station and operable over said circuit to operate said signal, a step-by-step element at each substation, and 70 means at the central station to operate said step-by-step device to select any desired signal for intermittent operation and to intermittently change the operative condition of the selected signal. 75

12. A signaling system having a central station and substations united by a line circuit, a signal at each substation, means controlled at the central station and operable over said circuit to operate said signal, a step-by-step element at each substation, and 80 means at the central station to operate said step-by-step device to select any desired signal for intermittent operation and to intermittently change the operative condition of the selected signal, said means at the central station including a source of current and switching means for transmitting impulses of alternate positive and negative character. 85

In witness whereof, I hereunto subscribe my name this 5th day of April, A. D., 1912.

OTTO T. LADEMAN.
